STRAIGHT KNITTING MACHINE

Emil J. Berger, Hatfield, Pa., assignor to Dex-
dale Hosiery Mills, Lansdale, Pa., a corporation
of Pennsylvania

Application June 10, 1937, Serial No. 147,438

5 Claims. (Cl. 66—82)

This invention relates to straight full fashioned stocking knitting machines of the "Cotton" type; and it has reference more particularly to flat full fashioned knitting machines in which the stockings are knitted complete with continuous leg and foot portions.

Incident to the production of a stocking blank on a machine of the sort specifically referred to, the machine is brought to a stop after the leg portion of the blank has been knitted, whereupon the loops across the central or instep portion of the blank are lifted from the mid group of the needles by a transfer point bar and held by the latter during the knitting of heel tabs with the end groups of needles. After the knitting and pressing off of the heel tabs, the loops held by the points of the transfer bar are restored to the instep needles, whereupon the heel tabs are swung outwardly at right angles to the body of the stocking and the loops of the inner selvage edges of such tabs impaled upon the end groups of the needles. Finally, the machine is again set in motion to knit the foot portion of the stocking in direct continuation. With the fine gauges of yarn and needles employed in the production of the light weight or "chiffon" stockings in vogue at the present time, any disalignment or variant spacing of the end groups of needles renders difficult the impalement of the selvage edges of the heel tabs and often results in loop dropping or gaping, and hence in the formation of imperfect junctures upon resumption of the knitting after the impaling step.

The primary aim of my invention is to overcome the above difficulty which objective I realize in practice as hereinafter more fully disclosed, through provision of a needle gauging means in the form of a bar with groups of points adjacent opposite ends thereof, adapted to be thrust into the intervals between the end groups of the needles to thereby definitely and evenly space said needles and so facilitate uniform impalement thereon of the loops along the inner selvages of the heel tabs.

Another object of my invention is to provide for the guidance of the gauging bar such that its points are caused to enter low in the intervals between the heel tab needles and to gradually move to a higher level in said intervals incident to advancement of said bar inwardly of the machine toward the needles.

Other objects and attendant advantages will appear from the following description of the attached drawings, wherein Fig. I is a fragmentary view in cross section of a flat knitting machine

embodying my invention, the needle bar of the machine being shown in its normal or operative position during the knitting of the heel tabs of a stocking blank.

Fig. II is a view like Fig. I, showing the needle bar retracted in readiness for the looping of the heel tabs of the stocking blank.

Fig. III is a fragmentary illustration in plan, viewed as indicated by the arrows III—III in Fig. II, with the needles of the machine and the gauging bar positioned in readiness for impalement of the inner selvage edges of the heel tabs upon the end groups of the needles.

Fig. IV is a fragmentary view corresponding to Fig. I on a larger scale showing the needle gauging bar in its normal inactive or idle position in the guides provided for its support.

Fig. V is a view like Fig. IV showing the needle gauging bar in an intermediate position in its guides.

Fig. VI shows one of the guides in perspective.

Fig. VII is a fragmentary view of the needle bar of the knitting machine showing the usual condition of the heel tab needles preparatory to being gauged in accordance with my invention;

Fig. VIII is a view similar to Fig. VII showing the heel tab needles uniformly gauged in readiness for the looping of the heel tabs of the stocking blank.

The knitting machine herein illustrated for convenience of exemplifying my invention is of well known construction and adapted for the successive production of full fashioned stocking blanks B complete with the leg and foot portions in integral continuation. Clamped in the longitudinally extending needle bar 1 of the machine are serially arranged needles of which the mid group designated 2 in Fig. III produces the instep portion A of the stocking while the groups 2a 35 beyond the ends of the mid group 2 are employed in the knitting of the heel tabs T. Incident to the knitting, the needles 2 and 2a cooperate in a known manner with sinkers 3 which are supported for horizontal in and out sliding movement in the stationary sinker bed 4. As ordinarily, the needle bar 1 is pivotally connected at 5 to its lifting arm 6 so that it can be swung from the active position shown in Fig. I to the angular retracted position shown in Fig. II to enable looping the inner selvage edges E (Fig. III) of the heel tabs T preparatory to the knitting of the foot portion of the stockings. The mechanism for actuating the bar 1 to move the needles in relation to the sinkers 3 incident to stitch 50 55

formation has been omitted from the drawings since it is not particularly pertinent to my invention. The sinkers 3 are given their advance or thread sinking movements in the customary manner through the medium of individually associated slur-cock-actuated jacks 7, and are retracted by a catch bar 8 in a well known manner. The draw off mechanism of the machine includes a take up reel 9 which is mounted on a longitudinally extending shaft 10, and whereto are secured straps 11 with hooks 12 at their free ends for engaging the usual draw rod 13 passed through the welt W (Fig. I) of the stocking blank B being knitted in the machine. As the knitting 5 proceeds, the rod 13 is drawn rearward under the pull of the straps 11 while sustained by a pair of laterally spaced horizontal rails 14 which are of angular cross section and which have their lateral outwardly-extending flanges 15 secured 10 by screws 16 to the longitudinal front rail or bed 17 of the machine frame. At 18 there is shown a transfer or point bar which is arranged to receive the fabric loops from the mid group 2 of the needles, which, as already explained, knit the instep portion of the stocking, said bar acting to hold the instep loops away from the needles 2 while the heel tabs T of the stocking blank are being knitted. The point bar 18 is suitably supported from above so that it can be moved from 15 a normal elevated position out of the way through the dot and dash line position shown at 18a in Fig. I to a position in which its points engage over the beards of the mid needles 2 to receive the fabric loops from them. After having 20 engaged the fabric loops on the mid needles 2, the bar is moved over the tops of said needles and positioned behind the latter as shown in full lines in Fig. I in which position it remains while the heel tabs are being knitted. Suitable means, 25 not shown, is provided in the machine for manipulating the point bar in the manner just explained, but inasmuch as this means is not directly concerned with my invention, it too has been purposely omitted from the drawings. After 30 the heel tabs T are formed and pressed off, the point bar 18 is again manipulated to restore the loops held thereby to the mid needles 2 from which said loops were previously taken, whereupon the machine is stopped for looping of the 35 inner selvage edges of the heel tabs onto the needles of the end groups 2a.

Owing to their frailty, the needles yield easily to sidewise flexure during impalement of the heel tab selvages and eventually become permanently 40 bent out of alignment as shown more or less exaggeratedly in Fig. VII, so that very often two needles will pass through the same selvage loop while others of the selvage loops are skipped, with consequent formation of imperfect junctures 45 50 when the knitting is resumed for production of the stocking foot. The means which I have devised for overcoming this difficulty includes a gauging bar 20 having adjacent its ends, groups of gauging points 21 which are adapted to be thrust into the intervals between the needles of the two end groups 2a. As shown in Fig. III, the gauging bar 20 generally resembles the topping bars ordinarily used in connection with full fashioned knitting machines except for the omission 55 of points at its center and except for lug projections 22 at opposite ends thereof arranged to engage longitudinal guide slots 23 (Figs. IV—VI) in the upright flanges of the rails 14 whereon the draw rod 13 is sustained during the knitting of 60 the stocking leg. At their rear ends, the slots 23

in the rails 14 are formed with downward recesses 24 which by coaction with the end lugs 22 of the gauging bar 20 hold the latter against accidental displacement in the normal retracted inactive or idle position shown in Figs. I and IV. At their 5 front ends, the slots 23 slope upwardly as at 25 so that when the gauging bar 20 is advanced toward the needles, it is gradually tilted relative to the horizontal as shown in Fig. V, and finally assumes a position at right angles to the needles 10 2a when the needle bar 1 is in its angularly retracted position as shown in Fig. II. The slots 23 in the bars are moreover downwardly notched at 15 their front ends as at 26 so as to hold the gauging bar 20 against displacement in its advanced 20 position.

The operation of my invention is as follows: Let it be assumed that the heel tabs T of the stocking blank B have been formed and pressed off as in Fig. III, the instep loops restored to the 25 mid needles 2, and the needle bar swung back to the retracted position of Fig. II, as hereinbefore explained, in readiness for the transfer of the inner selvage edges of said tabs. With this accomplished, the gauging bar 20 is advanced 25 from its normal retracted position, i. e., moved inwardly of the machine along longitudinal slots 23 in the supporting rails 14. At about the time that the gauging bar 20 reaches the inclined forward ends 25 of the slots 23, its points 21 enter 30 between the needles 2a well below the hooks of the latter, as shown in Fig. V. As the advancement of the gauging bar 20 continues, under the action of the inclines 25 at the front ends of the slots 23, the points 21 are moved upward in the 35 intervals between the needles of the group 2a until they finally reach the position shown in Fig. II at right angles to said needles at a higher level close to the beard tips of the latter. In thus moving upwardly between the needles 2a 40 from the position of Fig. VII to that of Fig. VIII, the points 21 of the gauging bar 20 cause said needles to be gradually flexed sidewise in one direction or the other, and when said bar finally occupies the notches 26 at the front end of the 45 guide slots 23, the needles 2a will be definitely and uniformly spaced as shown in Fig. VIII. It now remains for the operator of the machine to impale the loops of the inner selvage edges of the heel tabs T upon the needles 2a, which operation is rendered easy by reason of the accurate spacing of said needles so that the likelihood of loop skipping or dropping is substantially precluded.

Having thus described my invention, I claim: 55

1. In a straight knitting machine for producing a complete stocking blank with integrally-continuous leg and foot portions, a needle bar with a series of needles; means for receiving the fabric loops across the central or instep portion 60 of the stocking blank from the mid group of the needles and holding said loops during knitting of heel tabs on the end groups of the needles, and for subsequently restoring the instep loops to the mid needles upon completion of the heel tabs; 65 and means for uniformly spacing the end groups of the needles to facilitate impalement thereon of the selvage loops along the inner edges of the heel tabs in preparation for the resumption of the knitting to produce the stocking foot, said 70 means including a gauging bar normally retracted from the needles and having groups of gauging points adjacent opposite ends thereof corresponding to the needles of the end groups, and means for supporting and guiding the gaug- 75

ing bar during its advancement toward the knitting needles, to insure entry of its points into the intervals between the needles of the end groups.

2. In a straight knitting machine for producing a complete stocking blank with integrally-continuous leg and foot portions, a needle bar with a series of needles; means for receiving the fabric loops across the central or instep portion of the stocking blank from the mid group of the needles and holding said loops during knitting of heel tabs on the needles of the end groups, and for subsequently restoring the instep loops to the mid needles upon completion of the heel tabs; and gauging means for definitely and evenly spacing the needles of the end groups to facilitate impalement thereon of the selvage loops along the inner edges of the heel tabs in preparation for the resumption of the knitting to produce the stocking foot, said gauging means including a gauging bar with groups of points adjacent opposite ends thereof adapted to be thrust into the intervals between the needles of the end groups, and a pair of laterally-spaced rails with longitudinal slots engaged by projections at opposite ends of the gauging bar, whereby the latter is supported and guided during its advancement toward the knitting needles.

3. In a straight knitting machine for producing a complete stocking blank with integrally-continuous leg and foot portions, a needle bar with a series of needles; means for receiving the fabric loops across the central or instep portion of the stocking blank from the mid group of the needles and holding said loops during the knitting of heel tabs on end groups of the needles, and for subsequently restoring the instep loops to the mid needles upon completion of the heel tabs; and gauging means for definitely and evenly spacing the needles of the end groups to facilitate impalement thereon of the selvage loops along the inner edges of the heel tabs in preparation for the resumption of the knitting to produce the stocking foot, said gauging means including a gauging bar with groups of points adjacent opposite ends thereof adapted to be thrust into the intervals between the needles of the end groups, and supporting and guiding means for supporting and guiding the gauging bar during advancement toward the knitting needles and for causing the gauging points to enter low in the intervals between the needles of the end groups and to gradually move upward to a higher level in said intervals incident to the advancement of said gauging bar as aforesaid.

4. In a straight knitting machine for producing a complete stocking blank with integrally-

continuous leg and foot portions, a needle bar with a series of needles; means for receiving the fabric loops across the central or instep portion of the stocking blank from the mid group of the needles and holding said loops during knitting of heel tabs on the needles of the end groups, and for subsequently restoring the instep loops to the mid needles upon completion of the heel tabs; and gauging means for definitely and evenly spacing the needles of the end groups to facilitate impalement thereon of the selvage loops along the inner edges of the heel tabs in preparation for the resumption of the knitting to produce the stocking foot, said means including a gauging bar with groups of points adjacent opposite ends thereof adapted to be thrust into the intervals between the needles of the end groups, and a pair of laterally-spaced rails with longitudinal slots engaged by projections at opposite ends of the gauging bar, whereby the latter is supported and guided during its advancement toward the knitting needles, said slots having downward recesses at opposite ends which coact with the end projections of the gauging bar to hold it against accidental displacement in inoperative and operative positions.

5. In a straight knitting machine for producing a complete stocking blank with integrally-continuous leg and foot portions, a needle bar with a series of needles; means for receiving the fabric loops across the central or instep portion of the stocking blank from the mid group of the needles and holding said loops during knitting of heel tabs on end groups of the needles, and for subsequently restoring the instep loops to the mid needles upon completion of the heel tabs; and gauging means for definitely and evenly spacing the needles of the end groups to facilitate impalement thereon of the selvage loops along the inner edges of the heel tabs in preparation for the resumption of the knitting to produce the stocking foot, said means including a gauging bar with groups of points adjacent opposite ends thereof adapted to be thrust into the intervals between the needles of the end groups, and a pair of laterally-spaced rails with longitudinal slots engaged by projections at opposite ends of the gauging bar whereby the latter is supported and guided during its advancement toward the knitting needles, said slots being upwardly inclined at their inner ends to cause the gauging points of the bar to enter low in the intervals between the heel tab needles and to gradually move upward to a higher level in said intervals incident to advancement of said gauging bar as aforesaid.

EMIL J. BERGER.
